OPEN HEARTH FURNACE

Raoul Nissim, London, England

Application May 22, 1943, Serial No. 488,071
In Great Britain May 16, 1942

8 Claims. (Cl. 266—27)

The present invention relates to open hearth furnaces of the stationary and tilting types.

At present the normal open hearth furnace is charged through doors in the side walls of the furnace by means of a travelling charging machine which may serve a battery of four or five furnaces. The time taken to charge each furnace may amount to as much as between one and two hours, which in addition to involving the disadvantage of very serious loss in smelting time, also gives rise to the disadvantage that the charging and melting cycles of the several furnaces are out of phase so that they require separate and individual regulation and working; furthermore the quality of the metal produced in the several furnaces may be slightly different.

This difficulty can be minimised by making the charging doors as large as possible but the latter expedient introduces the further difficulty that whilst the doors are open cold air is aspirated into the furnace tending to cool the furnace and thus to damage the skewbacks and disintegrate the furnace lining particularly in the neighbourhood of the doors. Owing to the cooling of the furnace the fuel consumption is also greatly increased.

For these reasons it is usual to avoid charging an open hearth furnace with a light scrap since the lighter the scrap the longer is the time taken to charge it unless the scrap is given a preliminary conditioning treatment.

With a view to obviating these difficulties it has already been proposed to charge an open hearth furnace from above by hinging the whole furnace roof at one side so that it can be hinged upwardly to allow the charging from above.

A furnace built on these lines would, however, have the disadvantage that the stresses in the brickwork of the roof would be very different in the open position when the roof is "up ended" from those in the closed position, with the consequence that the brickwork would tend to disintegrate very rapidly. Furthermore, the under side of the roof when in the open position would be cooled to a very great extent whilst the height of the structure required to lift the whole roof in this manner would be very considerable.

It is also known to construct an open hearth furnace with a section of its roof removable. In the operation of such a furnace, charging is effected from above by first displacing the removable section of the roof right away from the furnace with the aid of a crane or the like, after which the charge is inserted into the furnace through the opening in the roof. Such a process

suffers from the disadvantage that the removable "charging section," each time it is swung away from the furnace, is thoroughly cooled, with the consequence that it rapidly deteriorates owing to the alternate heating and cooling to which it is subjected. Furthermore, it is not easy to crane the section back into place on the roof unless there is provided excessive clearance between the removable charging section and the adjacent fixed portions of the roof.

It is an object of the present invention to provide means whereby a furnace having an arched roof may be charged from above without introducing the disadvantages mentioned above.

With this end in view and in accordance with the invention there is provided an open hearth furnace having at least one "charging section" of its roof formed separately from the hearth and from the remainder of the roof; and means for transferring the said charging section longitudinally of the furnace from its normal or closed position so as to lie above another portion of the furnace roof thus leaving an opening in the roof through which the furnace may be charged from above.

The fact that the charging section is moved longitudinally of the furnace so as to be located immediately above another hot portion of the roof ensures firstly that the charging section is not unduly cooled, as it is kept comparatively hot by heat radiated from the roof, and secondly that the static condition of the section remains unchanged during the displacement.

A furnace constructed in accordance with the invention preferably comprises two charging sections located at the centre of the roof, each being a complete span, and if desired the remaining portion of the roof may also be constructed in sections each being a complete span separate from the charging sections and from the furnace hearth. By this means any one or more of these removable sections can be quickly and easily removed from the furnace roof for repair or replacement.

In charging the furnace each charging section (if there be more than one) is first lifted, so as to be clear of the remaining adjacent parts of the roof, and is then transferred longitudinally of the furnace so that it lies above another portion of the furnace roof, whereupon the furnace is charged from above by means of a basket-type charger.

The time taken to charge is, by this means, reduced to some few minutes, with the consequence that light scrap can be charged and,

since a battery of four or five furnaces are all charged within twenty minutes or so, the charging and smelting cycles are substantially in phase, thus simplifying the regulation and working of the several furnaces by virtue of the fact that they can be controlled as one.

Preferred embodiments of the invention will now be described with reference to the accompanying diagrammatic drawings in which:

Figure 1 is a longitudinal sectional elevation of an open hearth furnace constructed in accordance with the present invention.

Figure 2 is a perspective view of one charging section of a furnace roof.

Figures 3 and 4 are similar plan views of a furnace showing two charging sections in their closed and opened positions respectively.

Figure 5 is a longitudinal sectional elevation of a furnace having a modified form of roof.

Figure 6 is a longitudinal sectional elevation of a portion of the roof of a furnace and showing another modification of a charging section.

Figure 7 is a view similar to that of Figures 1, 5 and 6 but showing a roof having charging sections so constructed and arranged that they need not be lifted before being transferred longitudinally of the furnace, and

Figure 8 is a transverse section of an open hearth furnace having one or more of its roof sections formed with three hinge points.

In Figure 1 is illustrated a normal type of open hearth furnace with the exception that the centre portion of the arched roof is constructed in the form of two sections 10A and 10B, each of which comprises a complete span over the furnace from the front to the back walls. Henceforth each of these sections will be termed a "charging" section since it is by displacement of one or both of these sections that charging is effected. Each section can be lifted vertically so as to clear the remaining adjacent portions 10 of the roof and can be transferred longitudinally of the furnace into the position such as that shown at 10A so as to allow a charging basket 11 to be lowered into the furnace from above. The sections 10A and 10B can both be removed separately or together in which latter case a larger basket is employed.

It will be seen that when a charging section, such as 10B, is in its closed position the inner face of the charging section lies substantially flush with the inner face of the remaining portions 10 of the roof and when a charging section, such as 10A, is in its opened position it lies immediately above a hot part of the furnace roof and is thus prevented from cooling unduly.

Each charging section is constructed of refractory bricks enclosed preferably within a metallic framework and each section rests freely upon the longitudinal front and back walls of the furnace hearth; preferably in sand seals formed at the tops of these walls.

As illustrated in Figure 1, a hydraulic piston and cylinder 12 is used to rotate the wheels 13, around each of which run chains 14 by which the section 10A is lifted, whilst a hydraulic piston and cylinder 15 is used to transfer the trolley 16 which runs on rollers 17 and which carries the section 10A. The lifting and transferring mechanism may be operated pneumatically, electrically, by steam or in any other suitable manner. The furnace may be formed with one or more small side doors, one of which is shown at 18, for fettling the hearth or for the introduction of refining and correcting agents and for the working of the furnace generally.

In place of the hydraulic lifting and transferring mechanism illustrated in Figure 1 ordinary cranes may be used, and in any case the transferring and charging mechanism may serve a battery of furnaces.

One of the sections 10A and 10B is illustrated in perspective in Figure 2.

Figures 3 and 4 are diagrammatic plan views of the furnace illustrated in Figure 1, Figure 3 showing the charging sections 10A and 10B in their closed positions and Figure 4 showing the sections 10A and 10B in the opened positions.

Referring now to Figure 5, the whole roof of the furnace here illustrated is constructed in several sections, 19, 20, 10A, 21, 10B, 22 and 23, each of which is preferably a complete span across the furnace and two of which, the charging sections 10A and 10B, are removable for charging.

The longitudinal edges of all the sections may be provided with sand seals formed along the tops of the longitudinal front and back walls of the furnace. As each section is framed it may be lifted off the hearth for repairs. It will be seen that the whole of the roof in this modification is made up of a plurality of sections each of which is separate from the hearth and the remainder of the roof. The term "roof section" is used herein to describe any or all of these sections, the expression "removable section" is used to denote sections such as 19 which are removable for repair but which are not normally used for charging the furnace whilst the expression "charging section" is used to denote those sections which are normally used for charging. In order to complete the prevention of the escape or inlet of gas or air to and from the furnace the transverse edges of each section are provided with sand seals as shown in Figures 5, 6 and 7.

As in the case of Figure 1 the sections 10A and 10B of Figure 5 can be raised up from the remainder of the furnace roof by means of chains 14 and may be transferred horizontally by means of hydraulic jacks 15. Either one or both of the charging sections 10A and 10B can be transferred longitudinally of the furnace so that when the furnace is open for charging each section lies on top of another part of the furnace so that it is prevented from cooling rapidly and the life of the brickwork is thereby prolonged. The section 10A may be raised to the position shown in broken lines and is thereafter transferred to the left so as to lie above the removable sections 19 and 20.

The lifting and transferring mechanism may be of any known or suitable kind and preferably are inter-locked, so that only one can be operated at a time, by means of the apparatus described in United States Patent 2,313,837 when hydraulically operated. The same principle of interlocking may be applied when the lifting mechanism is other than hydraulic.

That portion of the roof above which lies a transferred section may tend to become over hot and therefore it may be necessary to provide means for cooling it. When this is done it is possible to relate the cooling of the roof with the movement of the charging section by an outer-locking arrangement similar to that described above.

When either one or both charging sections have been transferred to one side a charging basket is lowered into the furnace with the aid of a suitable crane.

When one of these charging sections has to be

taken away for repairs the chains 14 are disconnected from that section and the latter is removed with the aid of a crane, while the remaining i. e. the removable sections 19, 20, 21, 22 and 23 can be lifted directly by a crane.

As can be seen in Figure 5 the brickwork of each section is held within a strong steel frame or skewback such as that shown at 24 around section 10A. This frame is bound around all four edges of the section and the transverse members thereof are bridged by girders 25 by which the section can be lifted. Mechanical stresses set up in the brickwork due to the weight of the brickwork and thermal expansion are taken by this frame 24 so that the usual buckstays may be dispensed with.

The charging section illustrated in Figures 5, 6 and 7 are constructed in such a way that the longitudinal thrust of the expanding refractory material is supported by the metallic frame 24 which is itself protected by an adequate thickness of refractory material. Thus for example in Figure 5 bricks 49 are stepped up so as to raise the resultant thrust to the height of the metallic frame 24, whilst the frame 24 is protected from heat by the refractory bricks 49. If desired the metallic framework may itself be water-cooled.

Figure 6 illustrates another arrangement in which the underside of the charging section 10A lies flush with the brickwork of an adjacent section of the roof. As in the case of Figure 5 bricks 49 are stepped up so that the longitudinal thrust in the refractory bricks may be taken by the metallic frame 24 which is water-cooled as shown.

In the arrangement illustrated in Figure 7 the charging sections 10A and 10B are adjacent one another as in the case of Figure 1 and are so constructed and arranged that they need not be lifted before being transferred. Hinged flanges 26 on the charging sections are rotated so as to be withdrawn from sand seals 27 formed in the transverse edges of the adjacent portions 10 of the roof, after which the charging section is transferred longitudinally into the position shown at 10B.

It will be appreciated that, with this arrangement, and also that of Figure 6, all the metal framework is protected from the main heat of the furnace by a protective refractory lining. The metal framework serves to hold the bricks together and prevent them from disintegrating and falling into the furnace.

In order to preserve gas-tight seals between a charging section e. g. 10A and an adjacent removable portion e. g. 20 (Figure 5) of the roof, or along the joints formed between adjacent charging sections (Figures 1 and 7) or again between adjacent charging sections and a fixed portion of the roof, a trough is formed along the top of the transverse edge of one member into which dips a flange formed upon the adjacent member. The flange may be angularly rotatable so that it can be lifted out of the sand seal, before moving one or other of the adjacent sections.

In all cases the transverse sand seals are continuations of longitudinal sand seals formed between the longitudinal edge of a roof section and the hearth wall. Since each section, whether it be a charging section or a removable section, is protected by sand seals, any slight distortions of the roof do not affect the functioning of the furnace in any way, whilst the transverse sand seal joints permit one section to rise, as a result

of uneven thermal expansions, with respect to another.

Each charging section may be lifted either from above with the aid of chains secured to rings on the framework of the section or from below with the aid of jacks bearing against the underside of the longitudinal edges of the section.

As mentioned above, each roof section is held in a steel roof ring or frame so that when the refractory bricks of the roof expand as a result of an increase in temperature the apex of each roof section tends to rise. The resultant reactive force in each brick in these circumstances is, as is known, shifted so that it passes outside the middle third of the brick. So long as the resultant force lies within the middle third of the brick the latter remains wholly under compression, but as soon as the resultant force is shifted outside the middle third a portion of the brick is put under tension with the result that portions of the bricks tend to come apart and leave cracks, and the roof generally tends to disintegrate rapidly.

As shown in Figure 8, it is proposed to avoid this difficulty by, as it were, hinging each roof section both at its longitudinal rims 34 and 35 and along a longitudinal line at or near its pole or apex 36. Adjacent bricks 37 and 38 running along the apex are formed so as to be respectively concave and convex so that, when the crown of the furnace rises, as a result of thermal expansion, the two halves 39A and 39B of the roof section may pivot at the hinge point 36. At 40 is shown a flexible metal protective cover serving to prevent sand or the like falling into the joint 36.

The hinge points 34 and 35 at the longitudinal edges of the section are substantially similar. The section is supported by a frame or skew back 41 (corresponding with 24 of Figure 5) which may be hollow and formed with an aperture to allow a free flow of air within. Alternatively, it may be water-cooled. The skew back or frame 41 is formed internally with a convex portion 42 co-operating with a metal liner 43 secured to the outer brick 44 of the roof section. The liner 43 is externally concave of larger radius of curvature than that of the frame curve 42 so that, as the crown of the roof section rises under thermal expansion, the two halves 39A and 39B of the section pivot not only along the joint 36 but also at the longitudinal edges 34 and 35. A few bricks near each transverse edge are stepped up so that these edges may each dip into a sand seal 45 formed between the skew back or frame 41 and an upstanding portion 46 at the inner face of the hearth walls 47. Secured to the skew back 41 is a flexible protective metal cover plate 48.

As shown, the frame 41 is formed with the convex surface 42 and the edge of the roof section with a concave portion 43. The curvatures may, however, be reversed.

In United States Patent 2,313,837 there is described a furnace comprising a hearth and a roof either of which can be displaced laterally to allow for charging from above. The roof is loosely boxed within an auxiliary ring which in turn rests freely upon the hearth walls. The section of the auxiliary ring comprises an upstanding portion, spaced from but retaining the roof and two co-planar horizontal portions the inwardly directed one of which rests upon the top of the hearth walls and the outwardly directed one of which receives jacks located below the auxiliary ring. In the present invention the

charging and removable sections of the furnace roof may be located upon the furnace walls in the manner described in United States Patent 2,313,837, that is to say, with the aid of an auxiliary ring, and these sections may be lifted and transferred in any of the ways described in the same patent.

The sections may also rest on the hearth walls without the intermediary of an auxiliary ring and be lifted as described in the same patent specification.

What is claimed is:

1. An open hearth furnace including a hearth, a roof thereon having at least one roof section thereof formed separately from the hearth and from the remainder of the roof, said section being arched and formed in two parts which are hinged together along a longitudinal line in the neighbourhood of the crown of the furnace and along each of their longitudinal edges, means being provided for transferring at least one of said sections longitudinally of the furnace from its normal or closed position so as to lie above another portion of the furnace roof thus leaving an opening in the roof through which the furnace may be charged from above.

2. A furnace as claimed in claim 1, wherein adjacent bricks of the said two parts along the centre hinge line are formed respectively with co-operating cylindrically concave and convex surfaces.

3. A furnace as claimed in claim 1, wherein each roof section is encased by a metallic skew-back formed with cylindrically curved internal faces along its longitudinal members, which faces co-operate with correspondingly curved edge bricks of the roof section.

4. A furnace as claimed in claim 1, wherein each roof section is encased by a metallic skew-back which is hollow so that it may be cooled with suitable fluid.

5. A furnace as claimed in claim 1, including a protective cover over each of said hinge lines.

6. An open hearth furnace including a hearth, a roof thereon, having at least one charging section and at least one removable section, each

formed separately from the hearth and from the remainder of the roof, means for transferring the said charging section longitudinally of the furnace from its normal or closed position so as to lie above another portion of the furnace roof thus leaving an opening in the roof through which the furnace may be charged from above, a refractory roof section encased by a metal skew-back, and the brickwork of the section adjacent its transverse edges being stepped up in order that longitudinal thrusts due to thermal expansion are transmitted to the said skewback while the latter may be set back and thus protected from the heat of the furnace by a portion of the refractory brickwork.

7. An open hearth furnace including a hearth surmounted by a transversely arched roof having at least one charging section which is formed separately from the hearth and from the remainder of the roof, and which is of substantially the width of and the same transverse curvature as the roof, and means for transferring the said charging section longitudinally of the furnace from its normal or closed position, so as to lie above another portion of the furnace roof, thus leaving an opening in the roof approximately equal to the width of the roof, through which opening the furnace may be charged from above.

8. An open hearth furnace including a hearth surmounted by a transversely arched roof having at least one charging section and at least one other section, each of which is formed separately from the hearth and from the remainder of the roof, and is of substantially the width of and the same transverse curvature as the roof, means for mounting said other section so that same is in position of use during furnace operation, but is otherwise removable as a unit for repair or inspection, and means for transferring the said charging section longitudinally of the furnace from its normal or closed position so as to lie above another portion of the furnace roof, thus leaving an opening in the roof approximately equal to the width of the roof, through which opening the furnace may be charged from above.

RAOUL NISSIM.
